UNITED STATES PATENT OFFICE

2,681,698

COMBINED SHELTER AND CLOSURE FOR
LANDING PLATFORMSWalter Herman and Elmer C. Snyder,
Salina, Kans.

Application May 15, 1952, Serial No. 288,086

7 Claims. (Cl. 160—36)

1

This invention relates to new and useful improvements in sheltering devices for loading platforms and the primary object of the present invention is to provide a combined shelter and closure for loading platforms, wherein the same is readily moved from its closure forming position to its shelter forming position in a convenient manner.

Another important object of the present invention is to provide a combined shelter and closure for loading platforms involving a horizontal guide track that is secured to a building structure over an opening therein and which track slidably carries a pair of panels that may close the opening, the panels hingedly supporting panel sections that are extendable into the door opening of a car and one of the panels hingedly supporting a vertically swingable roof forming panel that will be supported over and by the panel sections to form a covered entrance from the building structure into the car.

A further object of the present invention is to provide a combined shelter and closure for loading platforms, so constructed as to permit the same to be employed with cars whose bottom walls are disposed at different heights.

A still further aim of the present invention is to provide a closure and shelter structure of the aforementioned character that is simple and practical in construction, strong and reliable in use, small and compact in structure, inexpensive to manufacture and install, and otherwise well adapted for the purposes for which the same is intended.

Other objects and advantages reside in the details of construction and operation as more fully hereinafter described and claimed, references being had to the accompanying drawings forming part hereof, wherein like numerals refer to like parts throughout, and in which:

Figure 1 is a front elevational view of a building structure and showing the present invention mounted thereon and in its closure forming position;

Figure 2 is a view similar to Figure 1 but showing the invention moved away from the opening in the building structure;

Figure 3 is a view similar to Figure 2 but showing the device arranged in its shelter-forming position.

Figure 4 is an enlarged vertical sectional view taken substantially on the plane of section line 4—4 of Figure 3;

Figure 5 is a horizontal sectional view taken substantially on the plane of section line 5—5 of Figure 4;

2

Figure 6 is an enlarged view in horizontal section taken on the line 6—6 of Figure 1, and

Figure 7 is an enlarged view in horizontal section taken on the line 7—7 of Figure 3.

Referring now to the drawing in detail, wherein for the purpose of illustration, there is disclosed a preferred embodiment of the present invention, the numeral 10 represents a horizontal header that is mounted by fasteners 12 or the like, to the outer face of a building structure S over an opening O in the building structure. The header 10 is open at its bottom and overlies and shields a horizontally disposed guide track 14 that is suitably secured over the opening O and to the building structure S.

A pair of vertically disposed horizontally slid-
able main panels 16 and 18 are supported by
the guide track 14 and their upper ends support
rollers 20 and 22 that engage the track 14 to
form the means whereby the main panels 16 and
18 are slidably supported by the track.

The inner vertical edges of the main panels 16
and 18 are hinged, as at 24 and 26, to the inner
vertical edges of a pair of horizontally swingable
auxiliary panel sections 28 and 30 that are swing-
able over the outer faces of the main panels 16
and 18. The auxiliary panel sections 28 and 30
may be swung perpendicular to the main panels
16 and 18. Chains 32 and 34 are attached to
the outer faces of the main panels 16 and 18
and their free ends carry hooks 36 and 38 that
will enter ears 40 on the auxiliary panel sections
28 and 30 to limit swinging movement of the
auxiliary panel sections to a position perpendi-
cular to the main panels 16 and 18 and parallel
to each other.

Vertical extensions 44 and 46 are provided
for the auxiliary panel sections 28 and 30. The
extensions 44 and 46 are hinged, as at 48 and 50,
to the opposed or outer faces of the auxiliary
panel sections 28 and 30. When the extensions
44 and 46 are not in use, they may be folded
against the outer faces of the auxiliary panel sec-
tions 28, 30, however, when the extensions 44
and 46 are in use they will extend forwardly from
the auxiliary panel sections.

The lower ends of the extensions 44 and 46
terminate short of the lower ends of the auxiliary
panel sections 28 and 30, and have extension flaps
52 and 54 hinged thereto, as at 56 and 58. When
not in use, the flaps 52 and 54 may be raised
to contact the outer faces of the extensions 44
and 46.

A vertically swingable roof-forming panel 60 is
hinged at one end, as at 62, to the upper end of
auxiliary panel section 28 and includes laterally

projecting side edge portions 64 and 66. The roof-forming panel 60 will extend between and will be supported upon the upper end of auxiliary panel section 30 when the auxiliary panel sections are disposed perpendicular to main panels 16 and 18. When the roof-forming panel is supported in this position, the inner side edge portion 64 will extend upwardly under the header 16 to prevent rain from entering the opening O or the shelter formed by the invention.

A roof-extension 68 is hinged, as at 10, to the outer edge portion 66 of the roof-forming panel 60 and will overlie the panel 60 when not in use. When the roof-extension 68 is being used, the same is swung forwardly against the edge portion 66 to extend upwardly and forwardly 15 of the roof-forming panel 60 as shown in Figure 4.

In practical use of the invention as a closure, the main panels 16 and 18 are moved toward each other and the panel section 30 is swung forwardly into edge to edge engaging relation to the main panel 16 as shown in Figures 1 and 6. When the device is used as a shelter, the auxiliary panel sections 28 and 30 are disposed perpendicular to the main panels 16 and 18 and hooks 36 and 38 are engaged in eyes 40 as shown in Figure 7. Extensions 44 and 46 are extended forwardly of auxiliary panel sections 28, 30 and roof-panel 60 is supported between and by said sections 28, 30. Extension 68 is swung forwardly and downwardly.

Extensions 44, 46 and roof extension 68 will extend into the opening of a car C to shelter the loaders and articles being moved from the building structure into the car or from the car into the building platform.

Having described the invention, what is claimed as new is:

1. A combined shelter and closure for loading platforms comprising a horizontal guide track adapted to be mounted over an opening in a building structure, a pair of vertically disposed horizontally movable main panels having their upper ends slidably engaged with the guide tracks for movement of the main panels toward and away from each other, each of said main panels having an inner vertical edge, an auxiliary panel section hingedly secured to the inner vertical edge of each main panel and movable to a position perpendicular to the main panels, and a roof-forming panel having an end hinged to the upper end of one of said auxiliary panel sections for vertical swinging movement and extendable over the upper end of the other auxiliary panel section when the auxiliary panel sections are disposed perpendicular to the main panels.

2. A combined shelter and closure for loading platforms comprising a horizontal guide track adapted to be mounted over an opening in a building structure, a pair of vertically disposed horizontally movable main panels having their upper ends slidably engaged with the guide tracks for movement of the main panels toward and away from each other, each of said panels having an inner vertical edge, an auxiliary panel section hingedly secured to the inner vertical edge of each main panel and movable to a position perpendicular to the main panels, and a roof-forming panel having an end hinged to the upper end of one of said auxiliary panel sections for vertical swinging movement and extendable over the upper end of the other auxiliary section when the auxiliary panel sections are dis-

posed perpendicular to the main panels, a horizontal header mountable over the guide track, said roof-forming panel having a laterally projecting inner side edge portion that extends upwardly under the bottom of the header when the roof-forming panel is disposed between the auxiliary panel sections.

3. The combination of claim 2 wherein said roof-forming panel also includes a laterally projecting outer side edge portion that extends from the same face of the roof-forming panel as the inner side edge portion, and an extension for the roof-forming panel hinged to the latter and resting against said outer side edge portion to extend upwardly and forwardly from the roof-forming panel when the latter is disposed between the auxiliary panel sections.

4. A combined shelter and closure for loading platforms comprising a horizontal guide track adapted to be mounted over an opening in a building structure, a pair of vertically disposed horizontally movable main panels having their upper ends slidably engaged with the guide tracks for movement of the panels toward and away from each other, each of said main panels having an inner vertical edge, an auxiliary panel section hingedly secured to the inner vertical edge of each main panel and movable to a position perpendicular to the main panels, and a roof-forming panel having an end hinged to the upper end of one of said auxiliary panel sections for vertical swinging movement and extendable over the upper end of the other auxiliary panel section when the auxiliary panel sections are disposed perpendicular to the main panels, a horizontally swingable extension for each auxiliary panel section and selectively movable against and outwardly of the auxiliary panel section, each of said extensions having a lower end terminating above the lower ends of the pair of main panels, and a vertically swingable flap hinged to the lower end of each extension and extendable downwardly from the extensions when the extensions are received in a car opening whose bottom wall is spaced well below the lower ends of the extensions.

5. A combined shelter and closure for loading platforms comprising a horizontal header adapted to be mounted over an opening in a building structure, a horizontal guide track also adapted to be mounted over an opening on a building structure and covered by the header, a pair of vertically disposed horizontally slidable main panels, rollers at the upper ends of the main panels slidably engaged with the tracks, said main panels having inner vertical edges, a pair of horizontally swingable auxiliary panel sections hinged to the inner vertical edges of said main panels and selectively movable over the main panels and to a position perpendicular to the main panels, a horizontally swingable extension for each auxiliary panel section and selectively movable against and outwardly from the auxiliary panel sections, a vertically swingable roof-forming panel hinged to the upper end of one of said auxiliary panel sections and foldable against said one of said auxiliary panel sections, said roof-forming panel adapted to extend between the auxiliary panel sections to be supported thereupon when the auxiliary panel sections are disposed perpendicular to the pair of main panels.

6. A combined shelter and closure for loading platforms comprising a horizontal header

adapted to be mounted over an opening in a building structure, a horizontal guide track also adapted to be mounted over an opening on a building structure and covered by the header, a pair of vertically disposed horizontally slidable main panels, rollers at the upper ends of the main panels slidably engaged with the tracks, said main panels having inner vertical edges, a pair of horizontally swingable auxiliary panel sections hinged to the inner vertical edges of said main panels and selectively movable over the main panels and to a position perpendicular to the main panels, a horizontally swingable extension for each auxiliary panel section and selectively movable against and outwardly from the auxiliary panel sections, a vertically swingable roof-forming panel hinged to the upper end of one of said auxiliary panel sections and foldable against said one of said auxiliary panel sections, said roof-forming panel adapted to extend between the auxiliary panel sections to be supported thereupon when the auxiliary panel sections are disposed perpendicular to the pair of main panels, said roof-forming panel having an inner laterally projecting side edge portion extending upwardly under the header when the roof-forming panel is disposed between the auxiliary panel sections.

7. A combined shelter and closure for loading platforms comprising a horizontal header adapted to be mounted over an opening in a building structure, a horizontal guide track also adapted to be mounted over an opening on a building structure and covered by the header, a pair of vertically disposed horizontally slidable main panels, rollers at the upper ends of the

main panels slidably engaged with the tracks, said main panels having inner vertical edges, a pair of horizontally swingable auxiliary panel sections hinged to the inner vertical edges of said main panels and selectively movable over the main panels and to a position perpendicular to the main panels, a horizontally swingable extension for each auxiliary panel section and selectively movable against and outwardly from the auxiliary panel sections, a vertically swingable roof-forming panel hinged to the upper end of one of said auxiliary panel sections and foldable against said one of said auxiliary panel sections, said roof-forming panel adapted to extend between the auxiliary panel sections to be supported thereupon when the auxiliary panel sections are disposed perpendicular to the pair of main panels, said roof-forming panel having an inner laterally projecting side edge portion extending upwardly under the header when the roof-forming panel is disposed between the auxiliary panel sections, and an extension for the roof-forming panel hinged to the latter and adapted to extend between and over the extensions for the auxiliary panel sections.
